[57] ABSTRACT

A hacksaw includes an integrally formed frame member providing a bridge section and outer and inner end sections depending therefrom. The inner end section has a reversely bent portion extending laterally to one side thereof to provide a transversely extending mounting arm at its free end and a spacing between the transversely extending mounting arm and the other arm of the reversely bent mounting portion. Handle means are provided on the inner end section and blade engaging means are provided on the outer end section adjacent the free end thereof for engaging one end of the hacksaw. Mounting means are provided on the mounting arm to engage the other end of the associated hacksaw blade. The blade engaging means on the outer end section includes a transversely extending pin projecting from one side surface thereof and a laterally offset leg portion adapted to bear upon the side surface of the associated hacksaw blade to retain it upon the transversely extending pin. The blade engaging means may also include a depending pin at the free end thereof so that the blade may be mounted in either horizontal or vertical disposition. The blade mounting means on the mounting arm includes a draw bolt assembly seated in a slot on the mounting arm, and the slot is desirably configured so as to permit 90° rotation of the draw bolt assembly for mounting of the saw blade in either horizontal or vertical positions.

HACKSAW WITH NOVEL BLADE MOUNTING MEANS

BACKGROUND OF THE INVENTION

Various structures have been proposed and marketed for use as hacksaws, most of which permit mounting of the blade in a vertical position relative to the hacksaw frame and some of which permit mounting of the blade in a horizontal position relative to the frame. In addition, devices have been proposed in which the hacksaw blade is not secured adjacent its outer end but is supported only inwardly from the outer end to provide an unobstructed end portion for operation in areas where there is little clearance.

Various structures have been proposed for providing a frame handle and blade tensioning means. Generally, such structures require a multiplicity of parts and consequent extensive assembly operations. As a result, hacksaw frame assemblies tend to be of relatively high cost if the materials of construction and the quality of fabrication are of first order. There has remained a need for durable, good quality but economical hacksaw frame assemblies and there has also remained a need to insure both safety and versatility in relatively inexpensive hacksaw frame assemblies.

Accordingly, it is an object of the present invention to provide a novel hacksaw employing a frame assembly with relatively few parts so as to permit economy of construction and facility of assembly.

It is also an object to provide such a hacksaw in which the blade may be pivoted upon the frame for use in either a vertical or a horizontal orientation.

Another object is to provide such a hacksaw in which the guard for the user's hand is integrally formed with the handle.

SUMMARY OF THE INVENTION

It has now been found that the foregoing and related objects can be readily attained in a hacksaw comprising a frame member integrally formed with an elongated bridge section, an outer end section depending from one end of the bridge section, and an inner end section depending from the other end of the bridge section. The inner end section has a first portion which is connected at one end to the bridge section and depends therefrom and it also has a base portion extending from the other end of the first portion in the direction of the outer end section in spaced relationship to the bridge section. The base portion includes a reversely bent mounting portion which extends laterally from the plane defined by the longitudinal axes of the bridge and end sections to provide a transversely extending mounting arm at its free end and a spacing between the transversely extending mounting arm and the other arm of the reversely bent mounting portion.

Handle means is provided on the inner end section for gripping of the hacksaw, and blade engaging means is provided on the outer end section adjacent the free end thereof for engaging one end of the hacksaw blade. Mounting means is provided on the mounting arm in substantial alignment with the blade engaging means of the outer end section for engaging the other end of the associated hacksaw blade in cooperation with the blade engaging means so as to engage firmly the hacksaw blade therebetween.

In the preferred embodiment, the blade engaging means on the outer end section includes a transversely extending pin projecting from one side surface thereof and adapted to seat in an aperture formed in the associated hacksaw blade. A depending leg portion is formed at the free end of the outer end section and is laterally offset in the direction of the pin and spaced from the pin towards the inner end section. As a result, this leg portion is adapted to bear upon the side surface of the associated hacksaw blade which is opposite that surface disposed against the surface of the outer end section about the pin so as to retain the end of the hacksaw blade upon the pin. The pin and leg portion are desirably integrally formed in the frame member with the pin being extruded from the material thereof and the leg portion being bent outwardly from the material thereof adjacent the free end of the outer end section.

The mounting means on the mounting arm includes a slot in the mounting arm and a draw bolt assembly seated in the slot, and the draw bolt assembly includes a draw bolt having a pin adapted to seat in an aperture formed adjacent the end of the associated hacksaw blade. In the preferred embodiment the draw bolt is of plate-like cross section with the pin formed adjacent one end thereof and with threads formed adjacent the other end thereof and a portion of reduced cross section intermediate the pin and the threads which may rotate in the slot of the mounting arm. Nut means is threadably engaged on the threads of the draw bolt to effect tensioning of the associated saw blade.

To permit mounting of the hacksaw blade in horizontal position, the blade engaging means on the outer end section includes a pin projecting from the free end thereof and adapted to seat in the aperture of the associated hacksaw blade, and the mounting means on the mounting arm includes draw bolt means which is pivotally mounted on the mounting arm to permit pivoting thereof. In its preferred aspect, the mounting arm has a slot which extends inwardly from the free end thereof with an L-shaped portion spaced inwardly from the free end, and the draw bolt means includes a draw bolt of plate-like cross section with a portion of reduced cross section intermediate its ends, which is adapted to seat in either one of the legs of the L-shaped portion of the slot.

In its preferred aspect, the handle means is formed with a generally vertically extending aperture therein to receive the fingers of the user and to provide a guard disposed towards the outer end section.

BRIEF DESCRIPTION OF THE DRAWINGS

FIG. 1 is a perspective view of a hacksaw embodying the present invention and adapted to orient the hacksaw blade only in vertical disposition;

FIG. 2 is a side elevational view thereof;

FIG. 3 is an elevational view of the opposite side thereof;

FIG. 4 is a plan view thereof;

FIG. 5 is a bottom view thereof;

FIG. 6 is an elevational view of the handle end thereof;

FIG. 7 is an elevational view of the opposite end thereof;

FIG. 8 is a fragmentary side elevational view thereof with the blade and draw bolt assembly removed and

with portions of the handle broken away to reveal internal construction;

FIG. 9 is a sectional view along the line 9—9 of FIG. 8 to an enlarged scale and with one-half of the handle assembly shown moved apart from the other half;

FIG. 10 is a sectional view along the line 10—10 of FIG. 8 to an enlarged scale;

FIG. 11 is a side elevational view of another hacksaw embodying the present invention with the hacksaw blade being shown in phantom line in the vertical disposition thereof;

FIG. 12 is a fragmentary elevational view of the hacksaw showing the hacksaw blade in phantom line in the horizontal disposition thereof;

FIG. 13 is a fragmentary perspective view of the outer end section of the hacksaw frame to an enlarged scale; and

FIG. 14 is a fragmentary perspective view of the mounting arm portion of the hacksaw frame to an enlarged scale.

DETAILED DESCRIPTION OF THE ILLUSTRATED EMBODIMENTS

Turning first to the embodiment of FIGS. 1-10, therein illustrated is a hacksaw utilizing the concepts of the present invention and generally comprised of an integrally formed frame generally designated by the numeral 10, a handle generally designated by the numeral 12, a draw bolt assembly generally designated by the numeral 14 and the hacksaw blade generally designated by the numeral 16.

Turning first in detail to the structure of the hacksaw frame 10, this is integrally formed from metal stock with an elongated bridge section 18, a depending outer end section 20 and a depending inner end section 22 which is best seen in FIG. 8. Adjacent the free end of the outer end section 20, the metal of the frame 10 is deformed so as to extrude or punch-out a transversely extending pin 24 from one side surface thereof. An elongated slot 26 extends inwardly from the free end of the outer end section 20 at a point spaced towards the inner end section 22 from the pin 24 to provide a depending leg 28. In turn this leg 28 is bent to provide an axial offset which defines a channel between its inner surface and the opposing surface of the outer end section 20 about the pin 24. As a result, the hacksaw blade 16 may be secured upon the outer end section 20 by seating the pin 24 in an aperture formed at the one end thereof and then pivoting the blade 16 into this channel so that the leg portion 28 will bear against the surface of the hacksaw blade 16 opposite that surface which is bearing upon the surface of the outer end section 20 about the pin 24. This minimizes any tendency for the hacksaw blade 16 to lift-off the pin 24 when the blade 16 is in the operative position.

Turning now to the inner end section 22 of the frame 10, this includes a first portion 30 of generally C-shaped configuration which is connected at its upper end to the bridge section 18, and a base portion 32 which is connected to the bottom end of the first portion 30. The base portion 32 in turn includes a reversely bent mounting portion 34 extending laterally from the plane defined by the longitudinal axes of the bridge section 18 and outer and inner end sections 20, 22, respectively. As a result of this configuration, the mounting portion includes a transversely extending mounting arm 36 at the free end of the base portion, an

intermediate web portion 38 and an inner arm 40 spaced from the mounting arm 36 so as to provide a channel therebetween. In this embodiment a slot 42 of generally T-shaped configuration extends inwardly from the free end of the mounting arm 36.

Seated in the slot 42 of the mounting arm 36 is the draw bolt or tensioning bolt assembly 14 which is generally comprised of the plate-like draw bolt 44 which has a pin 46 projecting from one side surface thereof and formed by staking from the metal of the draw bolt. At its opposite end the draw bolt 44 is provided with threads 48 on a shank portion of reduced width relative to the head or end from which the pin 46 is formed, and it can be seen that the head is of greater width than the width of the vertically extending portion of the T-slot 42 so as to prevent its being drawn therethrough. The draw bolt 44 also includes a portion of reduced width 50 intermediate the head portion bearing the pin 46 and the shank portion bearing the threads 48 so as to permit its rotation within the slot 42. Seated upon the draw bolt 44 is a washer 52 which bears against the surface of the mounting arm 36 and a wing nut 54 which is threadably engaged upon the threads 48. As a result, the hacksaw blade 16 may be seated upon the draw bearing assembly 14 by extending the pin 46 through the aperture formed adjacent the end thereof and it may then be tensioned by threading the wing nut 54 upon the draw bolt 44 to pull the inner end of the hacksaw blade 16 tightly towards the mounting arm 36.

As best seen in FIGS. 8 and 9, the bridge section 18 of the frame 10 is provided with an aperture 56 adjacent its juncture juncture with the inner end section 22. The handle 12 in turn is fabricated in two halves 58, 60 which have interfitting lips 62, 64 along their mating edges and which are joined together about the bridge section 18 and inner end section 22. The security of the assembly is enhanced by the lug 66 on the handle half 58 which seats in the aperture 56 formed in the bridge section 18. As seen, the handle halves 58, 60 have internal ribs and bosses to snugly fit about the bridge section 18 and inner end section 22 to provide a firm assembly, while at the same time minimize the amount of material required for the handle 12. The handle halves 58, 60 are provided with aligned elongated apertures therein which slope upwardly and forwardly to provide the finger receiving aperture 68 with the handle portion 70 forwardly thereof serving as a guard for the user's hand.

In the utilization of this embodiment, the hacksaw blade 16 may be mounted only in a vertical position with its teeth 72 extending either downwardly or upwardly as desired by the user. To assemble or change blades, the user first mounts the forward end of the blade 16 on the pin 24 with the blade extending generally downwardly from the outer end section 20. The hacksaw blade 16 is then pivoted upwardly into the recess defined by the depending leg portion 28 and the opposite end is snapped over the pin 46 upon the draw bolt assembly 14. Turning the wing nut 54 upon the draw bolt 44 will then tension the hacksaw blade 16 and secure it firmly in position.

Turning now to the embodiment of FIGS. 11-14, this is designed to accommodate the hacksaw blade 16 in either a vertical or a horizontal disposition relative to the plane defined by the principal axes of the bridge section 18 and end sections 20, 22 of the frame 10. In these figures, the same numerals are employed to desig-

nate the equivalent parts as had been employed with respect to the embodiment of FIGS. 1-10 and new numerals will be employed to designate additional or modified elements and features.

As best seen in FIG. 13, the outer end section 20 has a depending pin 74 extending from the free end thereof below the transversely extending pin 24 and it is dimensioned and configured to seat in the aperture of the hacksaw blade 16 when it is mounted in the horizontal position shown in FIG. 12. The mounting arm 36 of this embodiment is provided with a complexly configured slot generally designated by the numeral 76 and having a channel portion 78 extending inwardly from the free end thereof into an L-shaped portion provided by a leg portion 80 extending parallel to the free end and a leg portion 82 extending perpendicularly thereto. With the blade 16 in the horizontal disposition shown in FIG. 12, the draw bolt 44 is disposed in the leg portion 82 of the slot 76.

When vertical disposition is desired, the draw bolt 44 may be loosened by rotating the wing nut 54 to bring the reduced width portion of the draw bolt 44 into the slot 76 to permit its rotation. The draw bolt 44 may then be rotated so as to dispose it in the leg portion 80. To effect the change in disposition of the hacksaw blade 16, it is necessary initially to disengage the blade 16 from the pin 46 upon the draw bolt 44 and remove it from the pin 74 on the outer end section 20. The hacksaw blade 16 is then mounted upon the pin 24 and pivoted upwardly into the guide channel provided by the leg portion 28 and then snapped over the pin 46 on the draw bolt 44, following which the wing nut 54 is tightened to secure and tension the hacksaw blade 16.

It will be appreciated that various materials can be utilized for the fabrication of several components. Conveniently, the frame 10 is blanked from sheet metal stock and the bends therein are formed after staking of the pin and cutting and stamping of the slots necessary to form the offset leg and the mounting portion. The handle halves are desirably fabricated from synthetic plastic material and may be readily secured about the frame by ultrasonic welding, adhesives or other suitable techniques. Although other materials may be employed, it has been found preferable to utilize hardened steel for the draw bolt and nut so as to insure a rugged structure. It will be appreciated that variations in the illustrated configurations for the several components may be employed without deviating from the basic concepts of the present invention as may be other materials of construction.

Thus, it can be seen that the hacksaw of the present invention utilizes a relatively simple, economical and rugged frame assembly formed from a minimum of parts and permitting the use of highly durable materials. The hacksaw blade may be located in position and tensioned fully by a simple but durable assembly. In the one embodiment, the hacksaw blade can be oriented in either vertical or horizontal positions with relative facility and again utilizing a minimum number of parts.

Having thus described the invention, I claim:

1. A hacksaw comprising:

a frame member integrally formed with an elongated bridge section, an outer end section depending from one end of said bridge section and an inner end section depending from the other end of said

bridge section, said inner end section having a first portion connected at one end to said bridge section and depending therefrom and a base portion extending from said other end of said first portion in the direction of said outer end section in spaced relationship to said bridge section, said base portion including a reversely bent mounting portion extending laterally from the plane defined by the longitudinal axes of said bridge and end sections to provide a transversely extending mounting arm at its free end and a spacing between said transversely extending mounting arm and the other arm of said reversely bent mounting portion;

handle means on said inner end section;

blade engaging means on said outer end section adjacent the free end thereof for engaging one end of a hacksaw; and

mounting means on said mounting arm in substantial alignment with said blade engaging means of said outer end section for engaging the other end of an associated hacksaw blade and cooperation with said blade engaging means to engage firmly a hacksaw blade therebetween.

2. The hacksaw of claim 1 wherein said handle means is formed with a generally vertically extending aperture therein to receive the fingers of the user and provide a guard disposed towards said outer end section.

3. The hacksaw of claim 1 wherein said mounting means on said mounting arm includes a slot in said mounting arm and a draw bolt assembly seated in said slot, said draw bolt assembly including a draw bolt having a pin adapted to seat in an aperture formed in the associated hacksaw blade.

4. The hacksaw of claim 3 wherein said draw bolt assembly includes a draw bolt of plate-like cross section having said pin formed adjacent one end thereof and having threads formed adjacent the other end thereof with a portion of reduced cross section intermediate said pin and said threads, said reduced cross section of said draw bolt being seated in said slot of said mounting arm, said draw bolt assembly further including nut means threadably engaged on said threads of said draw bolt to effect tensioning of the associated saw blade.

5. The hacksaw of claim 1 wherein said blade engaging means on said outer end section includes a transversely extending pin projecting from one side surface thereof and adapted to seat in an aperture formed in the associated hacksaw blade.

6. The hacksaw of claim 5 wherein said blade engaging means also includes a depending leg portion at the free end of said outer end section laterally offset in the direction of said pin and spaced from said pin towards said inner end section, said laterally offset leg portion being adapted to bear upon the side surface of the associated hacksaw blade opposite that disposed against the surface of said outer end section about said pin so as to retain the end of the hacksaw blade upon said pin.

7. The hacksaw of claim 6 wherein said pin and said leg portion are integrally formed in said frame member, said pin being extruded from the material thereof and said leg portion being bent outwardly from the material thereof adjacent the free end of said outer end section.

8. The hacksaw of claim 5 wherein said blade engaging means on said outer end section includes a pin projecting from the free end thereof and adapted to seat in an aperture formed in the associated hacksaw blade,

and wherein said mounting means on said mounting arm includes draw bolt means on said mounting arm having a pin adapted to engage in an aperture at the other end of an associated hacksaw blade, said draw bolt means being pivotally mounted on said mounting arm whereby the hacksaw blade may be mounted on either of said pins on said outer end section and thus mounted for horizontal or vertical sawing action.

9. The hacksaw of claim 8 wherein said mounting arm has a slot extending inwardly from the free end thereof with an L-shaped portion spaced from said free end, said draw bolt means including a draw bolt of plate-like cross section with a portion of reduced cross section intermediate its ends adapted to seat in either one of the legs of said L-shaped portion.

10. The hacksaw of claim 9 wherein said blade engaging means also includes a depending leg portion at the free end of said outer end section laterally offset in the direction of said transversely extending pin and spaced from said transversely extending pin towards said inner end section, said laterally offset leg portion being adapted to bear upon the side surface of the associated hacksaw blade opposite that disposed against the surface of said outer end section about said transversely extending pin so as to retain the end of the hacksaw blade upon said pin in the vertical mounting thereof.

11. A hacksaw comprising:

a frame member integrally formed with an elongated bridge section, an outer end section depending from one end of said bridge section and an inner end section depending from the other end of said bridge section, said inner end section having a first portion connected at one end to said bridge section and depending therefrom and a base portion extending from said other end of said first portion in the direction of said outer end section in spaced relationship to said bridge section, said base portion including a reversely bent mounting portion extending laterally from the plane defined by the longitudinal axes of said bridge and end sections to provide a transversely extending mounting arm at its free end and a spacing between said transversely extending mounting arm and the other arm of said reversely bent mounting portion, said mounting

15

arm having an aperture therein; handle means on said inner end section; blade engaging means on said outer end section adjacent the free end thereof for engaging one end of a hacksaw; and

mounting means seated in said aperture of said mounting arm in substantial alignment with said blade engaging means of said outer end section, said mounting means including a draw bolt having means thereon for engaging the other end of an associated hacksaw blade and nut means on said draw bolt in said spacing between the arms of said mounting portion for drawing said draw bolt toward said other arm thereof, said mounting means cooperating with said blade engaging means to engage firmly a hacksaw blade therebetween.

12. The hacksaw of claim 11 wherein said blade engaging means on said outer end section includes a transversely extending pin projecting from one side surface thereof and adapted to seat in an aperture formed in the associated hacksaw blade and wherein said blade engaging means also includes a depending leg portion at the free end of said outer end section laterally offset in the direction of said pin and spaced from said pin toward said inner end section, said laterally offset leg portion being adapted to bear upon the side surface of the associated hacksaw blade opposite that disposed against the surface of said outer end section about said pin so as to retain the end of the hacksaw blade upon said pin.

13. The hacksaw of claim 11 wherein said aperture in said mounting arm is a slot extending inwardly from the free end thereof and wherein said means on said draw bolt for engaging the saw blade is a pin projecting therefrom adapted to seat in an aperture in a hacksaw blade.

14. The hacksaw of claim 13 wherein said blade engaging means on said outer end section includes a pin depending from the free end thereof and adapted to seat in the aperture of the associated hacksaw blade and wherein said draw bolt is pivotably mounted in said slot whereby the hacksaw blade may be mounted on either of said pins on said outer end section and thus mounted for vertical or horizontal sawing action.
